say Horace C. Spangler

Attorney

UNITED STATES PATENT OFFICE

THOMAS S. WHEELWRIGHT, OF RICHMOND, VIRGINIA, ASSIGNOR TO OLD DOMINION IRON & STEEL WORKS, OF BELLE ISLE, RICHMOND, VIRGINIA, A CORPORATION OF VIRGINIA

STAY BOLT

Application filed November 15, 1930. Serial No. 495,994.

This invention relates to flexible hollow staybolts for locomotive and other boilers which are subjected to excessive vibration, and particularly to that type of flexible stay-bolt which is provided with a rounded head, at one end, for flexible connection with the outer shell of the boiler and a tell-tale hole extending throughout the entire length.

Staybolts of the present type are usually manufactured from stock which has been severely tested to make sure that it conforms to very exacting specifications. However, as it has been customary to form the head of the bolt by a method requiring excessive heating of the stock, and form the tell-tale hole by drilling said stock, longitudinally, the nature of the metal is necessarily changed and injured to such an extent that the value of the inspection under specifications is wholly lost.

In view of the foregoing, it is an object of the present invention to produce a flexible tell-tale staybolt, of the headed type, wherein the stock has been provided with the tell-tale hole prior to the time of testing the same, and a further object to produce a bolt wherein the heading of the same is accomplished without subjecting the original stock to the heat required for forging the head.

In order to accomplish the first object mentioned, it is advisable to form the bolt of hollow rolled staybolt stock such as is set forth in United States Patents No. 1,618,142 and No. 1,668,705. Another reason for using hollow rolled stock is that the wall of the tell-tale hole is then protected from corrosion by the "skin" of the metal as well as by the silica flour which is burned into the said wall during the process of manufacture.

To accomplish the second object of the invention, the head is attached to the bolt by being threaded thereon or by being formed integral therewith by swaging or other process not requiring the application of heat, as more fully described later herein.

A further object of the invention is to provide a staybolt of the type mentioned wherein the tell-tale hole will extend entirely through the cap usually provided at the outer ends of such bolts, so that it will be possible

to inspect the same by inserting a testing instrument into the tell-tale hole without removing the said cap.

Other objects and advantages will be apparent from the following description when taken in connection with the accompanying drawing.

In the drawing:

Figure 1 is a sectional view showing one form of the invention.

Figure 2 is a sectional view showing another form of the invention.

Figure 3 is a fragmentary sectional view showing the device used for screwing the form of bolt, of Figure 2, into the inner boiler sheet.

Figure 4 is a detail sectional view showing the bolt seated directly in a seat in the boiler sheet, the sleeve not being used.

Referring particularly to the accompanying drawing, and especially to Figure 1, 10 represents a portion of the outer sheet of a steam boiler, while 11 represents a portion of the inner sheet thereof. In the outer sheet 10 there is formed an opening 12, having a smooth wall, while in the inner sheet 11, in direct alignment with the opening 12, is a threaded opening 13. Disposed within the opening 12, of the outer sheet, is a sleeve 14, said sleeve being welded to the outer face of the boiler sheet, as shown at 15. This sleeve projects inwardly, beyond the sheet, and also outwardly therebeyond, and on this outwardly projecting portion, external threads are formed.

Disposed through the sleeve 14, and the threaded opening 13, is the staybolt, which is represented as a whole by the numeral 16, said bolt having its inner end threaded into the opening 13, where such end is upset, as shown at 17, and its outer end provided with a head 18 having a rounded portion which rests in a seat formed in the sleeve 14. The head 18 is threaded onto the outer end of the bolt, and its outer face, which is flat, is provided with wrench receiving notches 19, whereby to permit screwing the bolt into the opening 13. This manner of attaching the head to the bolt obviates the necessity of heating the latter, resulting in danger to the

stock, as already set forth. A screw cap 20 is threaded onto the outer end of the sleeve 14, is dome-shaped, and is provided with an opening 21 in its crest, for a purpose which will presently appear herein.

The outer end of the body of the bolt extends slightly beyond the flat face of the head 18, and such projecting end is rounded, as shown at 23, to be received in a socket 24, formed in the inner end of a stem 25. The socket end of the stem 25 is slightly larger, in diameter, than the major portion thereof, whereby to provide a shoulder 25'. The outer end of this stem projects through the opening 21, of the cap 20.

Engaged on the stem 25 is a concavo-convex bearing washer or disk 26, preferably formed from brass, which bears against the inner concave surface of the cap 20, and disposed within the concavity of said disk is a packing disk 27, preferably formed of lead, or other suitable soft metal, which is compressible, and which can be forced into the joint between the disk 26 and the stem 25, whereby to render said joint steam-tight. Also disposed on the stem 25, and disposed against the packing disk 27, is a hard metal washer or bearing plate 28. Encircling the stem 25, and bearing respectively against the shoulder 25' and the plate 28, is a strong coil spring 29, which, when the parts are properly assembled, urges the disk 26 tightly against the inner face of the cap.

Formed longitudinally throughout the entire length of the bolt is a telltale hole represented by the numeral 30, which is formed in the stock, from which the staybolt is made, and which is described in my prior patents, 1,618,142 and 1,668,705, as already stated herein. This obviates the necessity of boring the telltale hole after the stock has been tested, for reasons already set forth.

Formed longitudinally and centrally through the stem 25 is an opening 16', which forms a continuation of the telltale hole 30, of the staybolt, the inner end of said opening 16' registering with the adjacent end of said telltale hole, as clearly seen in Figure 1.

In the form of the device shown in Figure 2, the head 31, of the staybolt 32, is formed integrally therewith. This may be done by swaging the metal into a suitable form, with the use of a swaging tool which will, at the same time, produce the conical socket 33. In this form, also, the stem 34 is provided with a rounded head 35, at its inner end, which rests in said conical socket 33. To provide for screwing this bolt into the threaded opening of the inner sheet of the boiler, a threaded recess 36 is formed at the bottom of the socket 33, to receive the threaded stem 37 of a conical member 38. This conical member is provided with wrench engaging faces 39, on its outer end.

If desired, the bolts hereinbefore described,

may be used without the sleeve, by positioning the head of the bolt directly on a seat 40, formed in the opening 41, on the boiler sheet, as shown in Figure 4. When this arrangement is used, the cap 20 may be welded directly to the boiler sheet.

What is claimed is:

1. In a staybolt structure, a casing comprising a sleeve and cap having outer and inner spherical seat surfaces, and said cap having an opening in its outer wall concentric with its seat surface, a bolt having an end portion disposed in said casing and provided with an inner head member having a spherical seat surface pivotally engaging the seat surface of the sleeve, an axial extension projecting beyond said inner head member and projecting outwardly through the opening in the cap, the bolt and its extension being provided with a tell-tale hole extending continuously from end to end thereof, an outer head member slideable on the bolt extension toward and from the inner head member and having a spherical seat surface pivotally engaging the seat surface of the cap, and resilient means acting to force the outer head member outward and away from the inner head member and against said seat surface of the cap.

2. In a staybolt structure, a casing comprising a sleeve and cap having outer and inner spherical seat surfaces, and said cap having an opening in its outer wall concentric with its seat surface, a bolt having an end portion disposed in said casing and provided with an inner head member having a spherical seat surface pivotally engaging the seat surface of the sleeve, an axial extension projecting beyond said inner head member and projecting outwardly through the opening in the cap, the bolt and its extension being provided with a tell-tale hole extending continuously from end to end thereof, an outer head member slideable on the bolt extension toward and from the inner head member and having a spherical seat surface pivotally engaging the seat surface of the cap, a packing member for closing the joint between the bolt extension and outer head member, and a spring for pressing the packing against the outer head member and acting to force the outer head member outward and away from the inner head member and against said seat surface of the cap.

3. A staybolt construction for use in connection with a boiler sheet having a seat and a centrally apertured cap secured in position over said seat, comprising a bolt having a head seated on said seat and provided with a stem extending beyond said head into said cap and through the aperture thereof, a centrally apertured spring pressed bearing disk on the stem having a face snugly and slidably contacting with a face of said cap, a packing against said disk, and means for

pressing said packing into the aperture of said disk and against said stem.

4. A staybolt construction for use in connection with a boiler sheet having a seat and a centrally apertured cap secured in position over said seat, comprising a bolt having a head seated on said seat and provided with a stem extending beyond said head into said cap and through the aperture thereof, a centrally apertured spring pressed bearing disk on the stem having a face snugly and slidably contacting with a face of said cap, a packing against said disk, and means for pressing said packing into the aperture of said disk and against said stem, said stem being movably engaged with said head.

In testimony whereof, I affix my signature.
THOMAS S. WHEELWRIGHT.
